HEAT-ACTUATED PENDULAR MOTOR

Jean Lorphelin, Paris, France

Application January 3, 1946, Serial No. 638,839
In France October 6, 1944

7 Claims. (Cl. 69—9)

1

My present invention relates to heat-actuated oscillating motors.

It is an object of my present invention to provide a heat-actuated oscillating motor which is reliable in operation and nevertheless simple in construction.

It is furthermore an object of my present invention to provide a heat-actuated oscillating motor by which it is possible to obtain an oscillatory movement of low frequency.

The novel features which I consider as characteristic for my invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a schematic front view of my new oscillating motor, partly in section; and

Fig. 2 is a cross section through one of the containers forming part of the motor of my invention shown in Fig. 1, along line 2—2 of Fig. 1.

My new heat-actuated oscillating motor comprises in combination a stationary support *a*, a turnable supporting frame *e*, a first closed container *R*₁ and a second closed container *R*₂ mounted on the turnable support *e* spaced from each other, and horizontal pivoting means *g* secured to the turnable support *e* at a point between the closed containers *R*₁ and *R*₂ so as to enable free turning of the turnable support *e* in direction of arrow *f* between two end positions in one of which the first closed container *R*₁ is in a lower position supported by abutment *B*₁ and the second closed container *R*₂ is in a higher position and in the other of which the first closed container *R*₁ is in a higher position and the second closed container *R*₂ in a lower position supported by abutment *B*₂.

Furthermore, my new heat-actuated oscillating motor includes two compartments in each of the closed containers *R*₁ and *R*₂ arranged so as to extend vertically adjacent to each other when the respective closed container is in the above defined lower position; each of these compartments has in such lower position an upper end and a bottom end. These compartments in the closed container *R*₁ are designated by the reference numerals *h*₁ and *i*₁ and the corresponding compartments in the closed container *R*₂ are designated with the reference numerals *h*₂ and *i*₂, respectively.

The compartments *h*₁ and *i*₁ in the closed con-

2

tainer *R*₁ are connected at their upper ends by a passage *k*₁, while the compartments *h*₂ and *i*₂ in the closed container *R*₂ are connected at their upper ends by the passage *k*₂.

Furthermore, the conduit *t* is arranged so as to connect the bottom end of the compartment *h*₂ with the bottom end of the compartment *h*₁, as clearly shown in the drawing.

As also clearly shown in the drawing, the containers and the compartments within the same are partly filled with liquid *m*.

Furthermore, I provide a heating coil *s*₁ connecting the bottom ends of the compartments *i*₁ and *h*₁ and the heating coil *s*₂ connecting the bottom ends of the compartments *i*₂ and *h*₂ as shown.

It should be mentioned that the preferably circular wall *c*₁ enclosing the compartment *i*₁ and the preferably circular wall *c*₂ enclosing the compartment *i*₂ are preferably made of insulating material.

It should also be mentioned that the tube portion *b*₁ of the heating coil *s*₁ and the tube portion *b*₂ of the heating coil *s*₂ are preferably enclosed in heat insulating blocks *d*₁ and *d*₂, respectively, which not only serve as insulating means but also contact the abutments *B*₁ and *B*₂, respectively, as shown in Fig. 1 of the drawing.

Finally, I wish to note that my oscillating motor includes a heating arrangement comprising the heating members *S*₁ and *S*₂. The heating member *S*₁ is arranged so as to heat the heating coil *s*₁ when the closed container *R*₁ is in its lower position and the heating member *S*₂ is arranged so as to heat the heating coil *s*₂ when the closed container *R*₂ is in its lower position.

In order to enable introduction and removal of the fluid *m* into and from the closed containers, I provide the spigots *P*₁ and *P*₂ in the walls of the containers *R*₁ and *R*₂, respectively.

It should be stressed that in order to enable adjustment of the oscillation periods of the entire motor, I provide the weight system *M* and *M'* slidably mounted on the rod *F* secured to the frame *e* by sliding of which it is possible to adjust the time needed for the entire system to turn from one of its end positions into the other.

My motor operates as follows:

At the start of operation, the motor is in the position shown in Fig. 1 with the liquid reaching to the level *I* indicated in the container *R*₂ and to the level *I'* indicated in the container *R*₁. Due to heating of the liquid in the heating coil *s*₂ by means of the heating member *S*₂, this liquid will vaporize and the formed vapors will ascend in the compartment *i*₂, pass through the passage *k*₂ and

exert pressure upon the surface of the liquid m in the compartment h_2 . This pressure will force the liquid m in the compartment h_2 through the open end of the conduit t into the same and through this conduit into the closed container R_1 which it will fill slowly.

It should be noted that due to the heat insulating block d_2 the gases will not escape through the tube portion b_2 , but this tube portion will only serve for admission of cold liquid.

After a certain period of time of heating of coil s_2 by flame S_2 , enough liquid will have passed through the conduit t into the closed container R_1 to force the same to turn about pivot g into the other end position of the motor in which the closed container R_1 is in its lower position with the heating coil s_1 located above the heating member S_1 .

This will occur the moment the liquid level in the closed container R_2 has dropped to the level indicated by II and the level of the liquid in container R_1 has reached the level II' .

It is evident that now the flame S_1 will heat the heating coil s_1 and force the liquid back through the conduit t into the closed container R_2 . This will continue until there is enough liquid in the container R_2 to force the same to turn back into its position shown in Fig. 1.

This oscillating to and fro turning movement is automatically and indefinitely continued as long as the heating members operate.

I wish to note that it is advisable to use as liquid a fluid which is saturated with gas at room temperature and at atmospheric pressure thereby decreasing the amount of heating necessary to obtain evaporation of the liquid.

I have found that liquids containing ammonia are particularly adapted for the purposes of the present invention.

It will be understood that each of the elements described above, or two or more together, may also find a useful application in other types of oscillating motors, differing from the types described above.

While I have illustrated and described the invention as embodied in heat-actuated oscillating motor, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention, and, therefore, such adaptations should and are intended to be comprehended within the meaning and range of equivalence of the following claims.

What I claim as new and desire to secure by Letters Patent is:

1. A heat actuated oscillating motor comprising in combination a stationary support; a turnable support; a first and a second closed container mounted on said turnable support spaced from each other; horizontal pivoting means securing said turnable support at a point between said closed containers freely turnably to said stationary support so as to enable free turning of said turnable support between two end positions in one of which said first closed container is in a lower position and said second closed container in a higher position and in the other of which said first closed container is in a higher

position and said second closed container in a lower position; two compartments in each of said closed containers arranged so as to extend vertically adjacent to each other when said closed container is in said lower position, each of said compartments having in such position an upper end and a bottom end; a passage in each of said closed containers connecting said compartments at said upper ends with each other; a conduit connecting said bottom end of one compartment of said first closed container with said bottom end of one compartment of said second closed container; a liquid partially filling all said compartments in said closed containers; and a heating arrangement arranged so as to be adapted to heat said bottom end of the other compartment of said first closed container when said turnable support together with said closed containers in that end position in which said first container is in said lower position and to heat said bottom end of the other compartment of said second container when said turnable support together with said closed containers in that end position in which said second container is in said lower position.

2. A heat actuated oscillating motor comprising in combination a stationary support; a turnable support; a first and second closed container mounted on said turnable support spaced from each other; horizontal pivoting means securing said turnable support at a point between said closed containers freely turnably to said stationary support so as to enable free turning of said turnable support between two end positions in one of which said first closed container is in a lower position and said second closed container in a higher position and in the other of which said first closed container is in a higher position and said second closed container in a lower position; stationary stop means arranged so as to prevent turning of said turnable support together with said closed containers beyond said end positions; two compartments in each of said closed containers arranged so as to extend vertically adjacent to each other when said closed container is in said lower position, each of said compartments having in such position an upper end and a bottom end; a passage in each of said closed containers connecting said compartments at said upper ends with each other; a conduit connecting said bottom end of one compartment of said first closed container with said bottom end of one compartment of said second closed container; a liquid which is saturated with gas at room temperature and at atmospheric pressure, said liquid partially filling all said compartments in said closed containers; a first heating device arranged so as to be adapted to heat said bottom end of the other compartment of said first closed container when said turnable support together with said closed containers is in that end position in which said first container is in said lower position; and a second heating device arranged so as to be adapted to heat said bottom end of the other compartment of said second closed container when said turnable support together with said closed containers is in that position in which said second container is in said lower position.

3. A heat actuated oscillating motor comprising in combination a stationary support; a turnable support; a first and second closed container mounted on said turnable support spaced from each other; horizontal pivoting means securing said turnable support at a point between said closed containers freely turnably to said station-

ary support so as to enable free turning of said turnable support between two end positions in one of which said first closed container is in a lower position and said second closed container in a higher position and in the other of which said first closed container is in a higher position and second closed container in a lower position; stationary stop means arranged so as to prevent turning of said turnable support together with said closed containers beyond said end positions; two compartments in each of said closed containers arranged so as to extend vertically adjacent to each other when said closed container is in said lower position, each of said compartments having in such position an upper end and a bottom end; a passage in each of said closed containers connecting said compartments at said upper ends with each other; a conduit connecting said bottom end of one compartment of said first closed container with said bottom end of one of said compartments of said second closed container; a heat insulating casing at least partly enclosing the other compartments in said closed containers which are not connected with each other by said conduit; a liquid which is saturated with gas at room temperature and at atmospheric pressure, said liquid partially filling all said compartments in said closed containers; a first heating device arranged so as to be adapted to heat said bottom end of the other compartment of said first closed container when said turnable support together with said closed containers is in that end position in which said first container is in said lower position; and a second heating device arranged so as to be adapted to heat said bottom end of the other compartment of said second closed container when said turnable support together with said closed containers is in that end position in which said second container is in said lower position.

4. A heat actuated oscillating motor comprising in combination a stationary support; a turnable support; a first and second closed container mounted on said turnable support spaced from each other; horizontal pivoting means securing said turnable support at a point between said closed containers freely turnably to said stationary support so as to enable free turning of said turnable support between two end positions in one of which said first closed container is in a lower position and said second closed container in a higher position and in the other of which said first closed container is in a higher position and said second closed container in a lower position; stationary stop means arranged so as to prevent turning of said turnable support together with said closed containers beyond said end positions; two compartments in each of said closed containers arranged so as to extend vertically adjacent to each other when said closed container is in said lower position, each of said compartments having in such position an upper end and a bottom end; a passage in each of said closed containers connecting said compartments at said upper ends with each other; a conduit connecting said bottom end of one compartment of said first closed container with said bottom end of one of said compartments of said second closed container; heat insulating means at least partly enclosing the other compartments in said closed containers which are not connected with each other by said conduit; a liquid which is saturated with gas at room temperature and at atmospheric pressure, said liquid partially filling all said compartments in said closed containers; a first heating device arranged so as to be adapted to heat

said bottom end of the other compartment of said first closed container when said turnable support together with said closed containers is in that end position in which said first container is in said lower position; and a second heating device arranged so as to be adapted to heat said bottom end of the other compartment of said second closed container when said turnable support together with said closed containers is in that end position in which said second container is in said lower position.

5. A heat actuated oscillating motor comprising in combination a stationary support; a turnable support; a first and a second closed container mounted on said turnable support spaced from each other; horizontal pivoting means securing said turnable support at a point between said closed containers freely turnably to said stationary support so as to enable free turning of said turnable support between two end positions in one of which said first closed container is in a higher position and said second closed container in a lower position; a weight member adjustably mounted on said turnable support so as to be adapted to be adjusted relative to said turnable support and thereby vary the distribution of weight of the same relative to said horizontal pivoting means; two compartments in each of said closed containers arranged so as to extend vertically adjacent to each other when said closed container is in said lower position, each of said compartments having in such position an upper end and a bottom end; a passage in each of said closed containers connecting said compartments at said upper ends with each other; a conduit connecting said bottom end of one compartment of said second closed container; a liquid partially filling all said compartments in said closed containers; and a heating arrangement arranged so as to be adapted to heat said bottom end of the other compartment of said first closed container when said turnable support together with said closed containers is in that end position in which said first container is in said lower position and to heat said bottom end of the other compartment of said second closed container when said turnable support together with said closed containers is in that end position in which said second container is in said lower position.

6. A heat actuated oscillating motor comprising in combination a stationary support; a turnable support; a first and a second closed container mounted on said turnable support spaced from each other; horizontal pivoting means securing said turnable support at a point between said closed containers freely turnably to said stationary support so as to enable free turning of said turnable support between two end positions in one of which said first closed container is in a lower position and said second closed container in a higher position and in the other of which said first closed container is in a higher position and said second closed container in a lower position; two compartments in each of said closed containers arranged so as to extend vertically adjacent to each other when said closed container is in said lower position, each of said compartments having in such position an upper end and a bottom end; a passage in each of said closed containers connecting said compartments at said upper ends with each other; a conduit connecting said bottom end of one compartment of said first closed container with said bottom end of one of said compartments of said second closed container; two heating coils each secured to the outer

surface of one of said closed containers and connected with the other of said compartments therein; a liquid partially filling all said compartments in said closed containers; a first heating device arranged so as to be adapted to heat said heating coil of said first closed container when said turnable support together with said closed containers is in that end position in which said first container is in said lower position; and a second heating device arranged so as to be adapted to heat said heating coil of the second closed container when said turnable support together with said closed containers is in that position in which said second container is in said lower position.

7. A heat actuated oscillating motor comprising in combination a stationary support; a turnable support; a first and a second closed container mounted on said turnable support spaced from each other; horizontal pivoting means securing said turnable support at a point between said closed containers freely turnably to said stationary support so as to enable free turning of said turnable support between two end positions in one of which said first closed container is in a higher position and said second closed container in a lower position; a weight member adjustably mounted on said turnable support so as to be adapted to be adjusted relative to said turnable support and thereby vary the distribution of weight of the same relative to said horizontal pivoting means; stationary stop means arranged so as to prevent turning of said turnable support together with said closed containers beyond said end positions; two compartments in each of said closed containers arranged so as to extend vertically adjacent to each other when said closed container is in said lower position, each of said compartments having in such position an upper end and a bottom end; a passage in each of said

closed containers connecting said compartments at said upper ends with each other; a conduit connecting said bottom end of one compartment of said first closed container with said bottom end of one of said compartments of said second closed container; a heat insulating casing at least partly enclosing the other compartments in said closed containers which are not connected with each other by said conduit; two heating coils each secured to the outer surface of one of said closed containers and connected with the other of said compartments therein; a liquid partially filling all said compartments in said closed containers; a first heating device arranged so as to be adapted to heat said heating coil of said first closed container when said turnable support together with said closed containers is in that end position in which said first container is in said lower position; and a second heating device arranged so as to be adapted to heat said heating coil of the second closed container when said turnable support together with said closed containers is in that position in which said second container is in said lower position.
